UNITED STATES PATENT OFFICE.

DENZIL C. BARNHILL, OF LA FAYETTE, INDIANA.

BREATH-GUARD.

1,101,898.

Specification of Letters Patent. Patented June 30, 1914.

Application filed October 16, 1913. Serial No. 795,549.

To all whom it may concern:

Be it known that I, DENZIL C. BARNHILL, a citizen of the United States, residing at La Fayette, in the county of Tippecanoe and 5 State of Indiana, have invented certain new and useful Improvements in Breath-Guards; and I do hereby declare the following to be a full, clear, and exact description of the invention, such as will enable others 10 skilled in the art to which it appertains to make and use the same.

This invention relates to a breath guard, especially adapted for use by a dentist while operating upon patients to prevent the former 15 from breathing the air exhaled by the patients, and likewise to protect the patient against breathing the air exhaled by the dentist.

The object of this invention is to provide 20 a device of this character which shall be simple, inexpensive to manufacture and entirely efficient in use.

Referring to the accompanying drawing wherein is shown an approved embodiment 25 of the invention, Figure 1 represents a perspective view of the invention in use, Fig. 2 represents a side elevation of the guard. Fig. 3 represents a central, sectional view therethrough, and, Fig. 4 represents a sectional view on the line 4—4 of Fig. 3.

Referring to the drawings in detail wherein similar reference numerals designate corresponding parts throughout the several views, the numeral 1 indicates the 35 body of the guard which is preferably of cylindrical formation and provided with a flared end 2. The opposite end of the body 1 is closed and provided with a pair of lateral extensions 3, the ends of which are of 40 suitable size and shape to snugly and comfortably fit within the nostrils of the wearer as clearly shown in Fig. 1. The ends of the lateral extensions 3, are preferably bulged slightly and conformably with the

interior of the nostrils whereby the device 45 will be self retaining.

The guard is preferably formed from a light and nonabsorbent material such as hard rubber, and its color is preferably pink, or nearly flesh colored, so as not to 50 detract the gaze of the wearer from his work.

As clearly shown in Fig. 1, the breath of the dentist, or operator, is discharged through the flared open end 2 of the guard 55 and directed to the side and behind the patient, while the dentist is working upon the right hand side of the patient. If the dentist wishes to work upon the opposite side of the patient, he simply reverses the 60 position of the guard so that his breath is directed to the left hand and behind the patient.

If desired, a suitable strainer carried by a ring 5 may be inserted within the flared 65 end of the body 1 so as to protect the dentist against particles liberated by his drill or the like. Further, if desired, a suitable packing 6 may be placed within the bulged portions of the extensions 3 and are preferably of absorbent material whereby they may be impregnated with a suitable medicine or purifier.

What I claim is:

A reversible breath guard consisting of a 75 hollow cylindrical body having a flared open end and a closed end, hollow nostril engaging extensions projecting laterally from the body at and adjacent the closed end thereof and communicating therewith. 80

In testimony whereof I have signed my name to this specification in the presence of two subscribing witnesses.

DENZIL C. BARNHILL.
